J. C. SMITH

ILLUMINATED ADVERTISING SIGN

Filed Sept. 30, 1926

John C. Smith, Inventor.

by Fisher, Fowle, Clapp & Sons, Atlys.

UNITED STATES PATENT OFFICE.

JOHN C. SMITH, OF CHICAGO, ILLINOIS.

ILLUMINATED ADVERTISING SIGN.

Application filed September 30, 1926. Serial No. 138,583.

This invention relates to illuminated advertising signs intended chiefly to take the place of the advertising globes now employed upon gasoline dispensing pumps and the like in connection with filling stations.

At present it is common to employ a flattened glass globe or a globe embodying a metallic rim or shell for glass panels, and this globe is usually mounted on the upper end of a gasoline dispensing pump with a suitable extension socket for receiving an electric lamp that illuminates the signs or advertising matter appearing on the panels or sides of the globe. However, these globes or the panels become readily broken when being shipped or transported and it frequently happens that an automobile will strike the pump and the globe or panels will break from the impact or jar. Furthermore, the lamp placed within the globe is not readily accessible owing to the necessity of removing the globe, and being comparatively large and fragile and therefore difficult to handle the globes are often broken, and while the electric lamp serves to properly illuminate the panels of the globe and the advertising matter appearing thereon, the illumination is limited to the globe and no light rays are cast upon the working parts or dial of the pump or other indicator which shows the quantity of gasoline being dispensed by the pump and thereby handicaps the attendant at night time.

The present invention provides an illuminated advertising sign or globe entirely of metal, thereby obviating breakage, and also provides a novel arrangement of electric lamps and reflectors which not only attractively illuminate the advertising matter appearing upon the opposite panels of the sign or globe but also result in highly illuminating the operating mechanism of the pump and the dials thereof or other mechanism which registers the volume of the liquid being dispensed, thereby facilitating the work of the attendant, as well as providing a non-breakable sign which can be readily attached to pumps now in use, and is also waterproof.

Other objects and advantages will be apparent as the description proceeds.

In the accompanying drawings:

Figure 1 is a side elevation of my novel illuminated advertising sign applied to the

upper end of a gasoline dispensing pump 55 or the like;

Fig. 2 is an enlarged transverse vertical sectional view taken on the plane of the section line 2-2 of Fig. 1; and

Fig. 3 is a fragmentary plan view of one 60 of the electric lamps and its reflector.

Referring to the drawings in detail, 4 designates the upper end of a gasoline dispensing pump or the like, which is usually provided with an upward extension having 65 a socket for receiving an electric lamp within and that illuminates a flattened glass globe mounted on the pump and bearing advertising matter. In the present instance such extension and socket are provided, but 70 the lamp and the glass globe are done away with and in lieu thereof a sign or globe 5, of substantially the same general outline as the old glass globes, is provided, except that the same is formed of sheet iron or 75 steel. It is made in two sections 6 secured together along a seam 7 and provided with a base 8 fitted within a tubular portion or neck 9 and suitably anchored thereto, as indicated at 10, while the upper end of the 80 neck is received within the flange 11 depending from the globe proper and secured thereto, as indicated at 12. The base 8 is adapted to be fitted upon and to be secured to the upper end of the pump 4.

The neck portion 9 is provided at diametrically opposite sides with openings 13 which receive a pair of sleeves 14 secured by integrally formed or attached collars 15 on their inner ends against the inner face of 90 the neck and attached by screws or the like 16. These sleeves carry a pair of lamp sockets 17 of porcelain, or other insulating or dielectric material, which have flanged outer ends 18 and between which and the outer ends of the sleeves, plates 19 are secured with their ends 20 bent over to form guideways or grooves 21. Set screws 22 are engaged through the sleeves 14 and with the sockets 17 for the purpose of anchoring the 100 sockets in position, and suitable wiring or insulated cord conductors 23 extend from the terminals of the sockets and connect to a plug 24 which is adapted to be inserted in a socket of the wiring system. The guideways or grooves 21 are adapted to receive the outwardly bent ends 25 of reflectors 26 consisting of oppositely tapered strips of

sheet metal with their ends directed at right angles or bent over to readily enter the guideways. These strips, owing to the resilient or springy character of the metal, 5 may be contracted to cause the sides and ends to move together and permit the bent portions thereof to enter the guideways so as to spread and retain the reflectors in position, and are preferably brightened with 10 white enamel or other reflecting surface at the inside to reflect the light rays from the sockets 17. Since the top and bottom portions of the reflectors are open, the light 15 rays will not only be reflected upon the opposite sides of the advertising sign or globe but will also be projected downwardly to the operating mechanism or indicators which control and show the amount of gaso- 20 line being dispensed by the pump or from the reservoir in certain types of apparatus.

In the form of the globe part proper of the sign, the central portions 28 of each of the side walls of the casing upon which the advertising matter is painted to advertise the product which is being dispensed or otherwise used, are concave and substantially in the form of sections of a sphere, and these parts are depressed or set in by means of 30 annular shoulders 29 from the peripheral portion of the sign, which is of rounding, or concavo-convex cross section. If the parts 35 28 were straight, the lower portions thereof would be more brightly illuminated than their upper portions, but when concave and substantially spherical, the light from the lamps does not strike as directly upon the lower portions of the sections 28 as it does upon the upper portions, so that the entire 40 surfaces of the sections 28 are uniformly illuminated notwithstanding the fact that the lamps are located at one point adjacent each edge of the surfaces to be illuminated. In other words, the shape of each section 28 45 compensates for the fact that different portions are located at different distances from the lamp. This is an important feature of the invention in conjunction with the mounting of the lamps with reflectors upon and 50 below the sign or globe, so that the light rays are not only cast upon the signs or advertising matter but will also be cast upon the operating mechanism of the pump to facilitate the work of the attendant beneath 55 the lamps and in the actuation of the mechanism controlling the quantity of gasoline being dispensed and other obvious purposes. In addition, the sign is non-breakable and can be readily attached to pumps now in 60 use. Furthermore, it is waterproof and may be readily shipped without fear of breakage, in addition to permitting convenient access to the lamps for the purpose of renewing same. In this connection, when a 65 replacement of a lamp is necessary or de-

sired, it is merely necessary to remove one of the reflectors or shades 26 in order to unscrew and remove the lamp, and after another lamp has been screwed into the socket, the reflector is replaced.

While I have shown and described my invention in a preferred form, I am aware that various changes and modifications may be made without departing from the principles of my invention, the scope of which is to be determined by the appended claims.

I claim:

1. An illuminated advertising sign including a metallic casing forming a globe and having opposite concaved sides substantially forming sections of a sphere, means for supporting the casing from beneath, lamps projecting from opposite sides of the supporting means outwardly of said sides, and reflectors around the lamps and open above 85 and below for the reflection of light rays in similar directions.

2. In a sign of the class described, a globe in the form of a metallic casing comprising sections clamped together and having opposed concave sides upon which the advertising matter is arranged, a base connected to the bottom portion of the globe and adapted for supporting the same upon a gasoline pump or the like, and illuminating means arranged beyond the edge of the globe at one point only on the periphery thereof and outwardly of the opposite sides thereof to reflect light rays uniformly over the sides and also downwardly.

3. In a sign of the class described, a globe in the form of a metallic casing having opposed concave sides upon which the advertising matter is arranged, a base connected to the bottom portion of the globe and adapted for supporting the same upon a gasoline pump or the like, sleeves projecting outwardly from opposite sides of the base, light sockets carried by said sleeves and having extension cords for connection with a lighting system, lamps arranged in said sockets, and reflectors carried by the sleeves around the lamps and open at the top and bottom.

4. In a sign of the class described, a globe in the form of a metallic casing having opposed concave sides upon which the advertising matter is arranged, a base connected to the bottom portion of the globe and adapted for supporting the same upon a gasoline pump or the like, sleeves projecting outwardly from opposite sides of the base, light sockets carried by said sleeves and having extension cords for connection with a lighting system, lamps arranged in said sockets, guides carried by the sleeves and sockets, and reflectors over the lamps comprising flexible strips bent in substantially U form with their ends directed outwardly to engage the guides, said reflectors being open at the top and bottom to direct light rays 130

on to the sides of the globe and downwardly.

5. An illuminated advertising sign including a non-vitreous globe with opposite concaved sides and an annular neck flange 5 on its periphery at its bottom, means on the flange for supporting the globe, and illuminating means carried by the supporting means attached to the neck at opposite sides and arranged radially outwardly of the globe, said illuminating means projecting beyond said concaved sides to reflect light rays upwardly and uniformly over said sides and also downwardly.

10. An illuminated advertising sign including a flattened metallic globe with concaved sides set in from the peripheral edges thereof, a base having a tubular portion connected to the globe at its periphery, oppositely extending sleeves carried by the tubular portion, lamp sockets in the sleeves, and lamps in the sockets projecting in opposite directions beneath the globe beyond its periphery to project light rays above to the sides of the globe and downwardly.

25. 7. An illuminated advertising sign including a flattened metallic globe with concaved sides set in from the peripheral edges thereof, a base having a tubular portion connected to the globe at its periphery, oppositely extending sleeves carried by the tubular portion, lamp sockets in the sleeves, and lamps in the sockets projecting in opposite directions beneath the globe beyond its periphery to project light rays above to the sides of the globe and downwardly, wiring 30 connections to the sockets, and a plug on the connections extending through the base.

8. An illuminated advertising sign including a globe with opposite concaved sides and an annular neck flange on its periphery 40 at its bottom, means on the flange for supporting the globe, and illuminating means carried by the supporting means attached to the neck at opposite sides and arranged radially outwardly of the globe, said illuminating means projecting beyond said concaved sides to reflect light rays upwardly and uniformly over said sides and also downwardly.

9. An illuminated advertising sign including a flattened globe with concaved sides set 50 in from the peripheral edges thereof, a base having a tubular portion connected to the globe at its periphery, oppositely extending sleeves carried by the tubular portion, lamp sockets in the sleeves, and lamps in the 55 sockets projecting in opposite directions beneath the globe beyond its periphery to project light rays above to the sides of the globe and downwardly.

10. An illuminated advertising sign including a flattened globe with concaved sides set in from the peripheral edges thereof, a base having a tubular portion connected to the globe at its periphery, oppositely extending sleeves carried by the tubular portion, lamp sockets in the sleeves, and lamps in the 60 sockets projecting in opposite directions beneath the globe beyond its periphery to project light rays above to the sides of the globe and downwardly, wiring connections to the sockets, and a plug on the 65 connections extending through the base.

JOHN C. SMITH.
